STEEL WOOL MACHINE

George B. Galvin, Springfield, Ohio

Application January 21, 1943, Serial No. 473,131

8 Claims. (Cl. 29—4.5)

1

This invention relates to machines for producing metal wool.

An object of the invention is to provide an improved metal wool-producing machine wherein the tension on the wire being cut is reduced to a minimum.

It is another object of the invention to provide a metal wool producing machine wherein a single wire passes beneath a plurality of cutting tools by passing through the machine many times so that the wire is cut down to its minimum size before being removed from the machine, and wherein the wire is independently driven each time it passes beneath a predetermined number of cutting tools.

Another object of the invention is to provide a metal wool-producing machine wherein a single wire is passed through the machine, and in its passage through the machine forms a plurality of loops that are independently driven so that each loop of the wire is only required to have tension thereon of sufficient quantity to draw it past a selected number of cutting tools, whereby the tension on the wire can be governed according to the tension capable of being absorbed by the smallest diameter wire and thereby preventing breakage of the wire in the machine.

It is another object of the invention to provide a metal wool forming machine wherein all of the cutting takes place on one side of the wire, and on one side of the machine, and a rotatable drum is provided for feeding the wire through the machine so that the tension on each loop of wire passing through the machine is the same and can be governed by the minimum tension that can be absorbed by the smallest size wire without breakage.

It is another object of the invention to provide a metal wool forming machine wherein a single wire in passing through the machine forms a plurality of loops so that the wire can be worked upon a number of times by a single cutting tool, the cutting tool being constructed and arranged so that it will remove approximately the same amount of wool from the wire each time the wire passes beneath the cutting tool.

Another object of the invention is to provide a new and improved cutting tool and holder for the tool for a metal wool forming machine.

Another object of the invention is to provide a new and improved cutting tool for a metal wool forming machine wherein the holder is adjustable in three different planes to provide complete angular adjustment of the cutting tool.

Another object of the invention is to provide a

2

metal wool forming machine wherein all of the cutting tools are positioned upon a single bed in the machine so that all of the cuts, made upon the wire, are produced on one side of the machine and all of the tools can be under the continuous observation of a single operator.

Another object of the invention is to provide an improved structural arrangement of a metal wool producing machine.

10 Further objects and advantages will become apparent from the drawings and the following description.

In the drawings:

Fig. 1 is a plane elevational view of the metal 15 wool producing machine of this invention with the wire supply roll and take-up roll shown somewhat diagrammatically.

Fig. 2 is a vertical cross-sectional view of the machine taken along line 2—2 of Fig. 1.

20 Fig. 3 is a front elevational view of the machine, a portion thereof being broken away to indicate the position of the cutting tools.

Fig. 4 is a side elevational view of a portion of the machine showing the manner in which a 25 single wire is wound about the driving drum and passes from one group of cutters to the next.

Fig. 5 is a cross-sectional view taken along 5—5 of Fig. 1 showing the pressure rolls for preventing 30 rotation of the wire when passing beneath the cutting tools of the machine.

Fig. 6 is a cross-sectional view of a portion of the driving drum showing the grooved surface 35 therein for guiding the wires around the drum.

Fig. 7 is a cross-sectional view of a cutting tool 40 engaging a plurality of wires for removing metal wool from each of the wires simultaneously.

Fig. 8 is an elevational view of a portion of the metal wool-producing machine showing the cutting tool holders in cross-section to illustrate the 45 construction thereof.

Fig. 9 is an end elevational view of a pair of cutting tools shown mounted in their holders and on the machine as viewed from the direction of the arrow A on Fig. 8.

Fig. 10 is a cross-sectional view taken along line 10—10 of Fig. 8.

In this invention the machine consists of a base member 10 that is provided with a gear box 11 (Figure 2) positioned substantially centrally 50 within the base member 10. The base 10 has a front ledge 12 that supports a vertical frame 13, which in turn supports the wire cutting unit 15. The base 10 is also provided with feet 16 that are adapted to rest upon a suitable foundation such 55 as the concrete blocks 17.

A rear ledge 13 is carried by the base 10 and supports a rear frame 20, a top frame 21 being positioned between the rear frame 20 and the front frame 13 and suitably secured thereto as with bolts 22. The front frame 13 is secured to the ledge 12 by means of the bolts 23 and the rear frame 20 is secured to the rear ledge 19 by means of the bolts 24.

The gear box 11 is provided with a bearing box 25 that supports a vertically disposed shaft 26 by means of the thrust bearing 27. Axle bearings 28 are provided in the bearing box 25 and the cover 29 for the gear box 11. The upper end of the shaft 26 is suitably bearinged in the bearing box 30 provided in the upper frame 21 by means of the anti-friction bearing member 31.

A drive drum 32 is secured to the shaft 26 and feeds the wire through the cutting unit 15 from which the metal wool is cut. The lower end of the drive shaft 26 carries a worm wheel 33 that is driven by a worm 34 secured upon a drive shaft 35 that is suitably bearinged in the gear box 11 and the bearing box 36 carried upon the rear ledge 19. A suitable electric motor 37, or other convenient source of power is connected to the drive shaft 35 for rotating the same and thus driving the drum 32.

The front frame 13 supports a plurality of cutting units 15, each of which, as shown in Figs. 8 and 9 consists of a base 38 that extends throughout substantially the entire height of the front frame 13 to support a plurality of cutting tool holders 40 upon arms 41 that extend outwardly from the base 38. The frame 13 is provided with a plurality of parallel recesses 42, one of which is shown in Fig. 8, to receive the base members 38 of the cutting units 15 which are suitably secured in these recesses. Each of the tool holders 40 is supported between a pair of the arms 41, a pair of tool holders 40 being disposed between each pair of arms 41.

Each of the tool holders 40 consists of a yoke member 43 that is provided with a channel shape slot 44 to receive a cutting tool 45 having a cutting edge 46. The cutting tool 45 is secured in position in the channel shape slot 44 by means of set screws 47.

The yoke 43 is provided with axially aligned holes 48 that receive the smooth shanks 49 of screws 50 providing means upon which the yoke 43 can pivot. The block 51 is supported upon an eccentric 53 that is carried upon the shaft 52. The eccentric 53 is provided with teeth thereon that form a worm wheel 54 that is engaged by a worm 55 provided upon a shaft 56 bearinged in the block 51. The shaft 56 is provided with a collar 57 that engages a sleeve 58 pressed into a bore 59 provided in the block 51 to retain the shaft 56 in the block 51. A suitable nut 60 is provided on the shaft 56 whereby the shaft is positioned within the block 51. When the shaft 56 is rotated the eccentric 53 will be rotated upon the shaft 52 to thereby move the block 51 toward or away from the base 38 of the cutting unit.

The shaft 52 extends throughout the length of each of the cutting units 15, as shown in Fig. 1, so that it supports all of the tool holders on a particular cutting unit 15. A retaining member 61 is provided with arms 62 that are adapted to co-operate with the arms 41 on the base 38 to retain the shaft 52 in position in the cutting unit 15, suitable screws 63 being provided to secure the retaining member 61 to the arms 41.

As previously mentioned the yoke 43 is pivotally mounted on the block 51 by means of the

screws 50. The yoke 43 can thus be moved at right angles to the axis of the shaft 52 to position the cutting tool 45 angularly to the axis of the shaft 52. To control the angular position of the yoke 43, and thus the cutting tool 45, a pair of set screws 64 are in threaded engagement with a ledge 64a on the block 51, and engage the yoke 43 upon opposite sides of the axis of screws 50 so that movement of the set screws 64 inwardly or outwardly will produce rotation of the block 43 about the pivot screws 50. Also, the block 51 together with the yoke 43 is rotatable on an axis coaxial with the eccentric 53, and thus upon an axis parallel with the axis of the shaft 52 so that the cutting tool 45 can be rotated about an axis parallel with the axis of the shaft 52. The angular setting of the tool 45, when the block 51 is rotated axially upon the eccentric 53, is controlled by means of the thumb screws 65. It will thus be seen that the cutting tool 45 is provided with three different adjustments. The first adjustment would be the thumb screw 65 to angularly position the cutting tool relative to the base 38 so that the cutting edge 46 will be disposed at a predetermined and selected angle for removing wool from wires that pass beneath the cutting tool. The second adjustment is the pivotal adjustment of the yoke 43 upon the screws 50 so that the cutting edge 46 of the cutting tool 45 can be adjusted angularly relative to the plane of cutting so that a single wire can be cut a number of times when passing under the same tool on a plurality of passes beneath the cutting edge of the tool. The third adjustment is 35 that accomplished by the rotation of the eccentric 53 whereby the cutting tool 45 can be moved perpendicular to the base 38 without altering the angular adjustment obtained by movement of the set screws 64, and the angular adjustment of the thumb screws 65 can be reobtained by merely turning them a predetermined number of revolutions.

A guide plate 66 is provided beneath each pair of cutting tools 45 and extends throughout the length of the machine, as shown in Fig. 1. The guide plate 66 is supported upon the front frame 13 and the base members 38 of the cutting units 15. Each guide plate 66 is provided with a plurality of parallel grooves 67 that are all of the same depth, the grooves extending throughout the length of the guide plate 66 so as to guide the wire in its path of travel beneath the cutting tool 45 when passing through the cutting units 15. In fact, each of the guide plates has two sets of grooves, one of which is disposed beneath each of the cutting tools 45 carried between a pair of arms 41, as shown in Fig. 9. As shown in Fig. 7 each set of grooves 67 consists of a series of twelve grooves so that a wire can pass beneath each cutting tool 45 twelve times, or twelve wires can be simultaneously passed beneath the cutting tool 45. If the same wire is passed beneath the cutting tool twelve times, as will hereinafter be described, it will be apparent each time that it passes beneath the cutting tool that the tool must be positioned somewhat closer to the guide plate 66 in order to engage the wire. As will be noticed in Fig. 7 the serrated cutting edge 46 of the cutting tool 45 is disposed angularly relatively to the plane of the surface of the guide plate 66 so that the uppermost edge 46a is closer to the guide plate 66 than the lowermost edge 46b. Therefore, each time the wire 70 passes beneath the cutting edge 46 a quantity of metal wool will be removed from the wire. The purpose of the

adjusting screws 64 now becomes apparent. It is to produce this angular position of the cutting tool 45. This arrangement avoids all necessity of precision grinding of the wire guide 66 with grooves of slightly different depth to take care of the decreasing size of the wire 70 as it progresses through the machine. In the machine of this invention a single wire passing through the complete machine will have 1,152 cuts made upon the wire because the wire passes beneath each of 96 tools twelve times.

In order to prevent the wire 70 from turning when being fed through the machine pressure rolls 71 are provided at each end of the guide plates 66, as shown in Fig. 1, each pressure roller being of a sufficient width to cover two groups of twelve wires each, as shown in Fig. 5. Each pressure roller 71 is carried in a slot 72 (Figure 8) provided in an arm 73 extending from the front frame 13 and a cover cap 74 secured to the arm 73 by means of the screws 75. Adjusting screws 76 engage opposite ends of the shaft 71 of each pressure roller 71 to adjust it angularly relative to the plane of the guide plate 66 to accommodate wires of varying thickness passing beneath the pressure roller 71, and thus prevent the wires from rotating in the grooves so that they will always present the original flat surface to the cutting tools 45 after the wire has started its travel through the machine.

To complete the description of the machine, an idler roll 78 is positioned at each end of the guide plate 66 adjacent the pressure rolls 71, as shown in Fig. 1. These idler rolls are provided with a series of grooves therein that are arranged in groups in the same manner as the group of guide grooves 67 in the guide plates 66 so that a wire passing from the plate 66 will have a groove in the idler roll that cooperates therewith to guide the wire over the idler roll 78. The surface of the drive drum 32 is also provided with a plurality of grooves therein, as shown in Fig. 6, so that the wire will be guided over the surface of the drum 32 while it is in engagement therewith.

A supply roll 80 having the wire 70 thereon is supported adjacent the machine in a suitable bearing support 81 so that it is freely rotatable. If desired, or if necessary, a suitable brake can be provided for the supply roll 80 so that it will not rotate faster than the wire can be used therefrom.

A wire straightener 82 is positioned between the supply roll 80 and the metal wool producing machine to remove all kinks and bends. Any conventional wire straightener can be used, but as shown herein a series of rolls 83 and 84 are positioned on opposite sides of the wire 70 and a similar set of rolls 85 is positioned at right angles to the plane in which the rolls 83 and 84 are positioned whereby all kinks and bends are removed.

The single strand of wire 70 is threaded over the idler rolls and beneath the cutting tools 45 in the cutting units 15 so that the strand of wire forms a plurality of loops that extend around the idler rolls 78 and the drive drum 32. As shown in Figs. 3 and 4, the single strand of wire is fed over the idler roll 78 on the lowermost groove 86. The wire is then carried over the drive drum 32 in the lowermost groove in the drum and returned to the feed roll 78 in the opposite end of the machine. As previously mentioned the grooves in the idler rolls and the drive drum are arranged in groups of twelve each, two groups of twelve being placed in align-

ment with, the two groups of twelve grooves provided in the guide plate 66, so that the wire is guided to and from the guide plate at each end thereof. After the wire has been wound around the idler rolls 78 and the drive drum 32 to completely fill the first group, or lowermost group, of grooves therein, the wire is then passed to the grooves associated with the second row of cutting tools disposed from the bottom upwardly of the machine, the wire crossing between the first and second set of grooves as shown by the angular position of the wire 70a, see Fig. 4. A single strand of wire is thus wound around the idler rolls, the drive drum and over the various guide plates for the various rows of cutting tools so that the single strand of wire 70 finally leaves the wool producing machine at the uppermost groove 87 provided in the idler roll 78 on the right-hand side of the machine, as shown in Fig. 3. This single strand of wire is then carried over a receiving roll 88 that is suitably bearinged in the bearing member 89 for rotation therein. When the strand of wire 70 leaves the machine it has been cut down to its minimum size, which is such a size that it would no longer stand any substantial tension for drawing the wire past a number of cutting tools.

The receiving roll 88 can be driven in any conventional manner so that the wire strand 70 is taken up from the machine just as fast as it is fed from the machine by the drive drum 32. The tension on the wire strand 70 leaving the machine should be maintained substantially uniform so that it will not break and thus cause a shut-down of the machine. Suitable tension control devices can be associated with the wire strand leaving the machine to control the tension thereof by regulating the speed of the receiving roll 88 to prevent breakage of the strand, or a variable speed drive mechanism can be associated with the receiving roll 88 to vary the speed of rotation of the receiving roll in accordance with the quantity of wire that has been received upon the roll so that a substantially constant tension will be maintained upon the wire strand 70.

Such a variable speed drive has been diagrammatically illustrated for driving the receiving roll 88 and consists of a variable speed drive unit 90 having sheaves 91 and 92 that are movable axially toward and away from one another with a belt 93 extending therebetween so that when the sheaves 92 are moved toward one another the sheaves 91 will be moved away from one another whereby the speed of rotation of the output shaft 94 of the variable speed drive unit 90 will be reduced. To control the movement of the sheaves 92 a rod 95 may engage the surface of the wire upon the receiving roll 88, whereby the rod 95 will be moved outwardly from the axis of the roll 88 as the layers of wire increase thereon. A suitable lever 96 can be operated by the rod 95 to control the sheaves 92 through a mechanism within the variable speed drive unit 90. Such mechanisms are well-known, as well as the general construction of the variable speed drive unit itself. Any one of the many types of units that are available on the general open market can be used in connection with this invention. A suitable manual control 97 may supplement the automatic control of the variable speed drive unit 90 to roughly set the output shaft 94 before the wool producing machine is started in operation.

From this invention it will be seen that a

single strand of wire is started into the wool producing machine at one end and is removed from the opposite end of the machine after it has been operated upon by the cutting tools of the machine 1152 times whereby the wire is reduced from its full diameter down to its minimum size before it is removed from the machine. Also, all of the cutting tools on the machine are available for constant inspection of a single operator without moving around the machine so that in case fault should occur at one of the cutting tools it can be immediately remedied before sufficient damage occurs to cause the machine to shut down.

Since a single strand of wire is used in the machine it will be apparent that the tension of the strand must be maintained uniform throughout its entire length to prevent breakage of the strand while it is passing through the machine. The driving arrangement for the strand which consists of the drive drum 32 of this invention is such that each loop of the strand of the wire 70 is individually driven and therefore only sufficient tension is required in each individual loop to draw it past the cutting tools in a single passage across the guide plates 66. Therefore, each loop of the wire is maintained under a minimum tension which can be regulated according to the tension of the minimum diameter of the wire that is being removed from the uppermost or last groove in the top guide plate just before the wire leaves the machine. Since tension on the wire is governed by the minimum size of the wire that is leaving the machine it is quite apparent that the wire strand will not break in any other portion of the machine because it is of a larger diameter in all other portions of the machine so that if the minimum tension will not break the wire just before it leaves the machine that it will not break in any other portion of the machine. Therefore, with the arrangement disclosed in this invention there is practically no danger of the breakage of a wire strand while passing through the wool producing machine.

While the form of the invention disclosed and described herein constitutes a preferred form, yet it is to be understood that the apparatus is capable of mechanical alteration without departing from the spirit of the invention, and that all such modifications as fall within the scope of the appended claims are intended to be included herein.

Having thus fully described my invention, what I claim as new and desire to secure by Letters Patent is:

1. A cutting tool for a wool producing machine which consists of a base member, a tool holder, a support block, a support shaft for said support block, means adjustably mounting said support block on said shaft for moving the support block normal to the shaft and substantially parallel thereto, means for rotatably adjusting said support block upon said shaft, and means adjustably mounting said tool holder upon said support block for rotation at right angles to said shaft.

2. A cutting tool for a metal wool producing machine comprising a base member, a shaft supported by said base member, an eccentric rotatably supported upon said shaft, a support block carried by said eccentric and means for rotating said eccentric therein to change the position of said support block relative to the axis of said shaft, means for rotatably adjusting said support block upon said eccentric to change the angular position of said support block relative to

said base member, a tool holder, pivot means normal to said shaft for mounting said tool holder upon said support block, and means for rotatably adjusting said tool holder upon said support block to change the angular relationship therebetween.

3. In a metal wool machine for a single strand of wire, a pair of idler rolls having grooves therein to independently receive a loop of a wire strand that passes through the machine, a drive drum of substantially larger diameter than said idler rolls having grooves therein for independently receiving a loop of the wire strand and positioned midway between said idler rolls with the periphery of said drum adjacent a plane extending across the periphery of said idler rolls whereby a wire strand may be threaded through the machine by passing the same over the surface of the idler rolls and said drum to arrange the wire in a plurality of loops thereover having a substantially triangular shaped arrangement so that each loop of the wire strand will be frictionally maintained under independent tension between said idler rolls and said drive drum, the tension of each loop being equal, a stationary and fixedly mounted guide plate disposed between said idler rolls having grooves of equal depth therein aligned with the grooves in said idler rolls for guiding the loops of the wire strand between said idler rolls, pressure rolls disposed adjacent each end of said guide plate to engage the cut faces of the wire passing thereover and prevent rotation of the wire strand passing across said plate, a plurality of cutting tools disposed adjacent said guide plate for removing wool from the wire strand passing across said guide plate, said cutting tools having cutting edges of a width sufficient to simultaneously engage a plurality of consecutively adjacent loops of the wire strand to simultaneously remove a substantially like quantity of wool from each of the loops engaged by the tool, means mounting said rollers so that their axes may be adjusted into parallelism with said cutting edges, means for adjustably and fixedly positioning the cutting edge of the cutting tool angularly relative to the plane of the guide plate to produce substantially uniform engagement with all of the loops of the wire strand engaged by the tool, means for adjusting said angular position of the cutting tool to change the cutting angle thereof relative to said guide plate, and means for adjusting the cutting tool toward or away from said guide plate without altering said angular position of said cutting tool.

4. A cutting tool for a metal wool producing machine that includes in combination, a base member, a shaft supported by said base member, an eccentric rotatably supported upon said shaft, a support block bearinged upon said eccentric for rotation thereon, means carried by said support block for rotating said eccentric upon said shaft whereby to move said support block parallel to said shaft, means adjustably interconnecting said base member and said support block for rotating said support block upon said eccentric, a tool holder, pivot means normal to said shaft for pivotally mounting said tool holder on said support block, and means adjustably interconnecting said tool holder and said support block for rotating the tool holder upon the support block to change the angular relationship therebetween and maintain the same irrespective of adjustments made by the first two mentioned adjusting means.

5. In a machine for producing steel wool by simultaneously shaving consecutive, substantially

coplanar passes of a single elongated wire, said passes determining a plane, a support, a shaft carried by said support parallel to said plane, a block pivoted on said shaft, a yoke adapted to receive and hold a tool, with its cutting edge in simultaneous shaving contact with all of said passes, and means pivotally mounting said yoke on said block whereby to vary the angle between the cutting edge of said tool and said plane.

6. A metal wool machine comprising a base, a tool support secured to said base along one edge thereof, a pair of rolls pivoted on said support on spaced parallel axes, a frame secured to said base and to said support, a shaft journaled in said base and frame on an axis parallel to the axes of said rolls, a driving drum of substantially larger diameter fixed to said shaft, said drum having a portion of its periphery closely adjacent the plane of the axes of said rolls and between said rolls, said drum and rolls having their peripheries grooved to guide a length of wire in a plurality of generally triangular loops thereabout, the loops between said rolls forming passes lying in a common plane, a plate fixed on said support having grooves of equal depth to receive the said passes so that said passes of wire slide thereover in said grooves, a tool shaft fixed to said support and overlying said plate normal to the travel of said passes, a block pivoted on said tool shaft, a yoke pivoted on said block on an axis normal to the axis of said tool shaft, said yoke being adapted to hold a cutting tool with its cutting edge in contact with all of said passes, means for adjusting said block about said shaft, and means for pivotally adjusting said yoke relatively to said block to vary the angular relation between said cutting edge and the plane of said passes.

7. In a machine for producing metal wool by simultaneously shaving consecutive parallel passes of a single strand of metal, said passes lying in a plane, a support, arms on said support, a shaft

carried by said arms with its axis substantially parallel and closely adjacent to said plane, block means journaled on said shaft, a tool carrier pivoted on said block on an axis perpendicular to the axis of said shaft, said carrier being adapted to hold a tool with its cutting edge in simultaneous shaving contact with said passes, means to fix said block means in adjusted position about said shaft, and means to pivotally adjust said carrier with respect to said block means, to vary the angular relation of said cutting edge and said plane.

8. In a machine for producing metal wool, a plate having parallel grooves therein of equal depth, means for moving a plurality of consecutive passes of a single length of wire in the same direction across and in contact with said plate, a cutting tool, means mounting said tool so that its cutting edge engages all of said passes to cut wool therefrom and at a predetermined angle to said plate, presser means adjacent said edge, and means mounting said presser means for angular adjustment relatively to said plate to engage the cut faces of all passes and hold said passes against said plate with substantially equal pressure while maintaining said faces in a common plane with said edge angularly to said plate.
